DESIGN FOR A BOTTLE

René Tricard, Paris, France, assignor to Lenthalic, Incorporated, New York, N. Y., a corporation of
New York

Application December 4, 1934, Serial No. 54,255

Term of patent 14 years

To all whom it may concern:

Be it known that I, René Tricard, a citizen of France, residing at Paris, France, have invented a new, original, and ornamental Design for a Bottle, of which the following is a specification, reference being had to the accompanying drawing, forming part thereof.

Figures 1, 2, 3, and 4 are, respectively, top, front, side, and rear views of a bottle embodying my new design.

I claim:

The ornamental design for a bottle as shown.
In witness whereof I affix my signature.

RENÉ TRICARD.
